UNITED STATES PATENT OFFICE.

FRANK STRUG, OF WILMINGTON, DELAWARE, ASSIGNOR OF ONE-HALF TO MIKOLAJ FERET, OF WILMINGTON, DELAWARE.

COLLAPSIBLE BED.

1,250,697.

Specification of Letters Patent.

Patented Dec. 18, 1917.

Application filed January 26, 1917. Serial No. 144,601.

To all whom it may concern:

Be it known that I, FRANK STRUG, a subject of the Emperor of Austria, resident of 5 Wilmington, county of New Castle, and State of Delaware, have invented certain new and useful Improvements in Collapsible Beds, of which the following is a specification.

This invention relates to improvements in 10 folding beds or couches, and has as its principal object the provision of a couch which may be extended and used as a bed or collapsed into such form as to be used as a seat.

A further object is to provide such devices in forms which may be readily operated and when in either position to have adequate strength, and to present a neat appearance.

These and other objects are attained by 20 the novel construction and combination of parts hereafter described and shown in the accompanying drawings, forming a material part of this disclosure, and in which:—

Figure 1 is a perspective view showing an 25 embodiment of the invention extended at length in position to be used as a couch or bed.

Fig. 2 is a similar view of the same, the 30 springs, mattress, and other coverings being removed.

Fig. 3 is a perspective view of the same shown in a folded or collapsed position.

Fig. 4 is a partial perspective view showing the supporting elements upon which the 35 mattress normally rests.

Fig. 5 is a partial perspective view showing the construction of the head or back rest portions of the device in a raised position.

Fig. 6 is a transverse sectional view taken 40 on line 6—6 of Fig. 1.

Fig. 7 is a partial perspective view indicating the several parts shown in Fig. 5 in a partially extended position.

Fig. 8 is a fragmental sectional view looking at the interior of the supporting means, and

Fig. 9 is a similar fragmental view looking at the same parts when in a folded position.

The side frames of the article are comprised of a plurality of elements combined at their ends and centers to corresponding elements forming in effect a pair of lazy-tongs, the extreme members 10 and 12 at one

end of which, together with the intervening elements are adapted to rest upon their ends on any level foundation.

Pivotaly engaged with the opposite end elements are the succeeding elements 12 and 13 having extending ends to the former of which is attached a cross-bar 14, a similar bar 15 being engaged with the lower ends of the elements 10, while at the head or opposite end is a transverse bar 16 similarly engaged with the lower end of the elements 11.

Pivotaly engaged with the upper ends of the elements 13 are the side members 18, the same being held in a rigid position by 70 means of transverse bars 20 near the ends, and a central bar 21 extending across near the center.

Also hingedly attached to the frame elements 18 are a pair of supports 22 adapted 75 to rest upon the floor and having secured between them a bar or tube 23 and engaged between the rod 23 and stretcher 16 is a hinged bar 25 so as to permit the frame to be raised or lowered as may be desired. 80

Engaged by means of the bracket 28 secured to the transverse bar 21 is a hinged lever 30 having at its upper end an eye 31, the lever being of such length as to extend and engage with the transverse bar 20 where 85 it may be held when in a vertical position by the clip 32.

A rope or strong cord 35 is secured at its ends to the foot bar 14, and extends above the lazy-tong elements upon each side of the 90 article, thence passing through openings in the frame sides 18 and eye 31 so that when the lever 30 is pendent that the cord is held rigid and level with the floor at such time as the lazy-tong elements are extended.

When it is desired to collapse or close the article, the lever 30 is raised, carrying the body of the cord 35 upward thereby materially shortening the same and causing the lazy-tong elements to close one upon another. 100

In addition to closing the article together, the cords 35 are used as supports for the springs upon which the mattress rests, the same consisting of relatively short, straight, 105 spring bars 38 disposed in parallel to the cords 35, their ends being connected by ringed loops 39 into which are engaged transverse bars 40, of the same general character as the longitudinally disposed bars, the 110

end and side elements being formed into eyes 42 which are engaged with the cords 35 as can best be seen in Figs. 1 and 3.

Upon the top of the spring elements 38 and 40 is disposed a flexible mattress 45 normally covered by a textile fabric 46, the covering being normally secured to the mattress by lacings 47 secured by tufts 48 at their ends, thus permitting the mattress covering and springs to be folded or collapsed into the position indicated in Fig. 9, when the article is to be used as a chair or seat, or if the article be extended to be used as a couch or bed, to present a substantially level surface as shown in Fig. 8.

Having thus described my invention, what I claim as new, and desire to secure by Letters Patent, is:—

1. In an article of the class described, the combination with a pair of lazy-tongs disposed in parallel and adapted to rest at one end upon the floor, of a rope secured at its ends to the outermost members of each pair of lazy-tongs, a frame engaged with the

opposite outer members, said rope engaging 25 with said frame, a stretching means for said rope, a bed spring having eyes engageable with said rope, and a mattress and covering disposed over said spring, said mattress, covering and spring being collapsible when 30 said lazy-tong elements are folded.

2. In an article of the class described, the combination with a plurality of lazy-tong elements, said elements being disposed in parallel, a frame hingedly engaged in the ends of said elements, supports for said frame, means for holding said supports in an extended position, a flexible spring support engaged with the opposite ends of said lazy-tong elements, a lever through which 40 said supporting means passes hingedly engaged with said frame, and means for holding said lever in either a lowered or raised position, whereby said elements are held in an extended or retracted position.

In testimony whereof I have affixed my signature this 7th day of December, 1916.

FRANK STRUG.
